UNITED STATES PATENT OFFICE.

THOMAS B. ALDRICH, OF DETROIT, MICHIGAN.

INHALER.

Application filed October 18, 1920. Serial No. 417,620.

The invention relates to inhalers designed for use in the treatment of the nose and throat and consists in the novel construction as hereinafter set forth.

5 In the drawings:

Figure 1 is a sectional elevation;

Figure 2 is a cross-section;

Figure 3 is a perspective view.

In the construction of inhalers it is usual 10 to fill the same with granular or powdered material, through which the air is drawn, becoming charged with the vapor of the volatile matter during its passage. The amount 15 of vapor generated is proportional to the surface exposure and the velocity of the air in passing over the same and therefore with a granular or powder body there is no uniformity of action. Various medicinal substances are manufactured in tablet form for 20 convenience in shipment and in use, but as far as I am aware, such tablets have never been employed in inhalers. I have discovered that by constructing an inhaler so as to receive tablets of the volatile material, 25 the amount of surface exposure can be definitely controlled, with the result that the vapor charging of the air will be uniform. Furthermore, the construction is one which facilitates the original charging of the inhaler with the medicinal substances, as well 30 as the renewal of the same whenever necessary.

As shown, A is a container, preferably of tubular form and preferably formed of 35 glass. B is a nose or mouth piece formed at one end of the container, which as shown is of a flattened bulbular form connecting with the container A by a contracted neck portion C and provided with an aperture 40 D at its outer end. The opposite end of the container A is preferably opened for its full diameter, being provided with a bead E for the attachment thereto of a cap F, preferably of rubber. This cap has a restricted aperture G in the end thereof, permitting the ingress of air, but too small for 45 the escape of the tablets H. The latter are preferably of a size to form a single pile within the tubular container, but with sufficient clearance peripherally for the passage 50 of the air. The tablets may be of any form, but preferably are of the usual oval form, which permits the air to pass between as well

as around the same, forming in effect a series of baffles.

In use the inhaler is charged with tablets of any desired medicinal material, the number of tablets determining the amount of surface exposure. Thus with highly volatile materials a number of tablets would be preferable than with less volatile substances. Also, if it is desired to strongly charge the air with vapor, a greater number of tablets may be used than where a weaker charge is desired. Thus any desired effect may be 65 readily obtained.

When the air is drawn through the inhaler by suction on the nose or mouth piece, it will impinge upon successive tablets, finally passing through the neck C and aperture 70 D. Whenever necessary, tablets may be renewed or if desired, the same container may be used with tablets of different materials.

To suitably mark or label the inhaler, the 75 label is placed inside of the cylindrical tube A and is attached to the walls thereof. The dimensions are, however, such that a transparent slot is left between the adjacent ends through which the tablets are visible. Thus, while the greater part of the cylindrical surface is covered, the number and condition of the tablets can be ascertained by viewing the same through the transparent slot.

What I claim as my invention is:

1. An inhaler comprising a glass tube for 85 receiving a series of tablets having an open end, a contracted portion and a suction piece beyond said contracted portion, and a cap resiliently engageable with said container for retaining said tablets and apertured for 90 the ingress of air.

2. An inhaler comprising a glass tube adapted to receive therewithin a series of tablets arranged in a pile, said tube being open at one end and having a contracted 95 neck portion and a suction piece attached to said neck, a label arranged within said tube extending around the same to leave a space between its ends through which the tablets are visible, and a cap for the container apertured for the ingress of air.

3. An inhaler comprising a container having a cylindrical barrel portion open at one end, and adapted to receive a series of volatile tablets of a diameter slightly less than 105 the internal diameter of said barrel portion,

a retaining cap engageable with said open end and provided with a small air inlet, and a suction nozzle at the opposite end of said barrel joined thereto by a restricted portion 5 forming a retainer for said tablets.

4. An inhaler comprising a glass tube having an open beaded end, a series of tablets

arranged within the tubular portion, and a resilient cap for retaining said tablets apertured for the ingress of air, and adapted to 10 be retained in position by said beaded end.

In testimony whereof I affix my signature.

THOMAS B. ALDRICH.
